UNITED STATES PATENT OFFICE.

LEO ABELES, OF PHILADELPHIA, PENNSYLVANIA.

SIGNALING DEVICE.

1,070,096.

Specification of Letters Patent. Patented Aug. 12, 1913.

Application filed November 27, 1912. Serial No. 733,734.

To all whom it may concern:

Be it known that I, LEO ABELES, a citizen of the United States, residing at Philadelphia, in the county of Philadelphia and 5 State of Pennsylvania, have invented certain new and useful Improvements in Signaling Devices, of which the following is a specification.

My invention relates to improvements in 10 signaling devices, and more particularly to an improved signal device which is adapted for attachment to the rear of an automobile, and which also supports a license tag, and at night illuminates the tag, so that it 15 can be seen from a distance.

A further object is to provide an improved construction of signal device comprising a plurality of compartments containing lights under the control of the chauffeur or operator, so that various signals 20 may be given to cars approaching from the rear, and also provide an improved means for illuminating the license tag by means of a lamp inclosed in a compartment of the 25 casing, and having its light reflected downwardly and at an angle through a transparent section of the casing against the license tag.

With these and other objects in view, the 30 invention consists in certain novel features of construction and combinations and arrangements of parts as will be more fully hereinafter described and pointed out in the claims.

35 In the accompanying drawings: Figure 1 is a view in front elevation illustrating my improved signaling device showing in dotted lines the position of the license tag. Fig. 2 is a view in side elevation of Fig. 1. 40 Fig. 3 is a perspective view of the transparent section of the casing wall. Fig. 4 is a view in vertical longitudinal section on the line 4—4 of Fig. 2. Fig. 5 is a view in section on the line 5—5 of Fig. 1 showing 45 a part of the central partition broken away. Fig. 6 is an enlarged fragmentary section illustrating the manner of securing the glass front in the door, and Fig. 7 is a fragmentary view in section on the line 7—7 of 50 Fig. 1.

55 Fig. 1 represents a cylindrical casing, the back plate 2 of which is extended below the casing and provided with slots 3 to facilitate the attachment of a license tag 4 as indicated in dotted lines in Fig. 1.

The cylindrical casing 1 is normally closed

by a door 5 hinged at one side as shown at 6, and at its opposite side provided with a hasp 7 to receive a staple 8, and secured in place by any approved locking device, a 60 simple hook is illustrated, but it is to be understood of course, that various changes might be made in this particular.

The door 5 comprises a metal ring having a flange 10 to fit within the casing, and 65 the outer portion of said ring, in cross section, bent in the arc of a circle as illustrated at 11. In the ring, a circular piece of glass 12 is located and held by means of a binding wire 13 against a shoulder 14 in the ring. 70 This binding wire 13 is curved in the arc of a circle, and at its ends is bent outwardly forming lugs 15 which are adapted to be grasped and moved toward each other to contract the wire, and allow the same and 75 the glass to be removed. When, however, the wire is in operative position, it will securely hold the glass in place and render it practically dustproof as well as prevent rattling which might be liable to break the 80 glass.

The glass 12 is rendered opaque in any 85 approved manner, except at certain points where transparent letters are formed.

The casing 1 is divided by an upper horizontal partition 16, a vertical partition 17, and a reflector partition 18 into four separate compartments 19, 20, 21, and 22 respectively, each compartment having its 90 light or lamp 23.

While, of course, this invention is not limited to any particular type of lamp, in the several compartments I preferably employ a bar light, as such lights do not cast shadows and give to the letters a better appearance than could be had by the ordinary incandescent lamp.

While I have not shown any wiring, I would have it understood that it is my intention to wire all the lights inside of the 100 casing, and connect all of them through an opening 24 in the back of the casing to the source of electricity supply and to the switch mechanism for controlling the lights. It is to be understood, of course, that the several 105 wires to the different lights will be run through the partitions, and openings (not shown) will be provided for the purpose.

The glass 12 in front of compartment 19 contains the letters spelling the word 110 "Stop". In front of compartment 20, the letter "L" is formed in the glass 12, and

in-front of compartment 21, the letter "R" is formed in the glass 12.

When the lights of the several compartments are connected with the source of electricity supply, the different signals will be given. For example, the word "Stop" will indicate to a car approaching from the rear that the chauffeur proposes to stop his car. The letter "L" will indicate that the chauffeur proposes to turn to the left, and the letter "R" will indicate that he proposes to turn to the right.

The bottom of compartment 22 is closed by a transparent section 25 preferably of glass, and which conforms throughout the greater portion of its length to the general curvature of the cylindrical wall of casing 1. The metal wall of casing 1 constituting the greater portion of the circumference of said casing, at its ends, is bent forming hooks 26, and the ends of the transparent section 25 are bent forming oppositely positioned hooks 27. When this section 25 is slid into place from the front, its hooked ends 27 will engage the hooked ends 26, so that the transparent section will be properly located. When the door 5 is closed, this transparent section will be securely held.

The reflector partition 18, while it separates compartments 20 and 21 from the compartment 22, also serves as a reflector to throw the light down upon the license tag. With this end in view, the partition 18 is inclined upwardly from front to rear as shown most clearly in Fig. 5, and the ends of the partition incline downwardly so that the light is not only thrown downwardly, but is directed rearwardly toward the license tag, and the rays of the light are centered upon the license tag.

On the back 2, a sleeve 28 is secured and is adapted to be connected to any approved form of bracket and secured in place by a set screw 29.

In order to accommodate license tags of various lengths, I provide sliding extensions 30 located at the back of plate 2 and having sliding connection therewith. Tongues 31 are bent backwardly from the plate 2, and extend through longitudinal slots 32 in extensions 30. These tongues securely hold the extensions, yet permit them to slide freely so that they may be adjusted in ac-

cordance with the length of the tag. The extensions are shown extended in full lines 55 in Fig. 1, and in dotted lines in their concealed position in Fig. 4.

It will thus be seen that my improved signaling device also operates as a license tag holder, and while I have described and shown what I believe to be a preferable arrangement of parts, I would have it understood that various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In a signaling device of the character described, the combination of a cylindrical casing having an opening in its bottom, the end walls of said opening curved inwardly, partitions dividing said receptacle into a plurality of chambers, one chamber including the said opening, a transparent section 80 having hooked ends adapted to be slid into the said opening with the ends overlapping the end walls of the opening, and a door covering the said chambers and having transparencies in front of the same.

2. In a signaling device of the character described, the combination of a cylindrical casing having an opening in its bottom, partitions dividing said receptacle into a plurality of chambers, one chamber including 90 the said opening, a transparent section curved concentrically with the curvature of the casing, and having sliding interlocked engagement with the walls of the opening, and a door covering the said chambers and 95 having transparencies in front of the same, said door when closed engaging the edge of the transparent section and holding the same in place, substantially as described.

In testimony whereof I have signed my name to this specification in the presence of two subscribing witnesses.

LEO ABELES.
